DIAPER COMBINATION

Wilma Gesund, Detroit, Mich.

Application October 9, 1942, Serial No. 461,432

5 Claims. (Cl. 2—111)

The present invention pertains to a novel diaper combination for infants, consisting of a shirt or bodice member and a nether garment.

The principal object of the invention is to provide such a combination wherein the attachment of the nether garment to the bodice member does not require pins or buttons. Consequently, injury to the infant is prevented.

Another object of the invention is to provide a number of fastening elements between the bodice member and the nether garment, of such character that separate manipulation for unfastening is not required. In other words, a single pull on the nether garment releases the fastenings.

In the accomplishment of these objects, the fastening elements consist of tabs on the ends of the nether garment or sheet and these tabs are adapted for insertion in corresponding slots in the bodice member. The tabs have heads considerably wider than the slots so that they are pulled out only by means of considerable force in the proper direction. Each tab also includes a neck forming acute angles with the edges of the head of the tab, whereby the latter is more securely locked in the corresponding slot.

Another object of the invention is to provide and maintain a moisture proof lining member within the nether garment. In this connection, the nether garment is a two-ply member closed at two opposite edges. The lining member is fitted neatly between the plies and carries the previously mentioned tabs. The tabs extend through slots in the closed edges of the nether garment and are adapted for insertion in the slots in the bodice, as previously mentioned. Thus, the lining member is maintained neatly and smoothly within the nether garment.

The invention is fully disclosed by way of example in the following description and in the accompanying drawing in which

Figure 1 is a front elevation of the device;

Figure 2 is a detail elevation;

Figure 3 is a perspective view of the nether garment;

Figure 4 is a perspective view of the outer portion of the nether garment; and

Figure 5 is a perspective view of the lining of the nether garment; and

Figure 6 is an elevation partly in section of the bib.

Reference to these views will now be made by use of like characters which are employed to designate corresponding parts throughout.

In Figure 1 is shown a shirt or bodice mem-

ber 1, the upper portion of which may be of any conventional or desired construction. With reference to the lower portion, it should be noted that the lower edge 2 is intended to extend only a short distance below the waistline. The intermediate portion of the lower edge 2 is cut concave at 3 at front and back. This formation, in conjunction with the short length of the shirt, does away with excessive material and with the discomfort that usually results therefrom.

Near the lower edge is formed a number of slots 4 horizontally arranged and preferably four in number, two in the front and two in the back, and all near the sides. The purpose of these slots will presently appear. Between the slots at each side of the garment there may be attached two cords or ribbons 5 which may be tied together for adjustment at the waistline.

The nether garment is a sheet having two plies 6 closed at the end or horizontal edges as indicated by the numeral 7. The lateral edges 8 are open and may be shaped to form a comfortable opening for the legs of the infant. In this connection it will be understood that, in use, the two horizontal edges are brought upward, so that the sheet is folded through the crotch of the infant, whose legs are received in the lateral openings.

Between the two plies 6 is provided an inner lining sheet 9 of similar shape. This sheet is of a moisture proof material, such as rubber or rubberized fabric. The closed ends 7 of the two-ply member are slotted at 10 to correspond with the slots 4 in the bodice member. Fabric binding strips 9' are stitched to the ends of the sheet 9. Linen tabs extend from the strips 9' through the slots 10, each such tab comprising a neck 11 as wide as the slot 10 and a head 12 of a greater width.

When the nether garment is fitted in the crotch of the infant as previously described, the tabs 11, 12 register with the slots 4 and pass therethrough. The slots 4 are substantially the same width as the slots 10, so that the heads 12 must be folded in order to be inserted therein. After insertion, however, the heads 12 are flattened out so that they overlap the ends of the slots 4. In this manner the heads are locked in both the slots 10 and 4 but can be removed by a downward pull on the nether garment.

Adjacent to its neck 11, each head 12 has straight edges 13 forming acute angles with the longitudinal edges 14 of the neck. These angles further assist in preventing the heads from being accidentally pulled through the slots.

Below the slots 4, the bodice may carry buttons 4' for attachment of over-pants, should these be worn.

At each side of the neck opening 15 of the bodice is a short strap 16 having one or more button holes 17. The straps hold the bib shown in Figure 6.

The bib consists of a two-ply folded fabric sheet 18 with an inserted rubber or other water-proof sheet 19. To the upper edge of the latter is stitched a binding strip 20, with tabs 21 extending therefrom and carrying buttons 22. The tabs extend through slots 23 in the folded edge of the sheet 18 and the button holes 17 of the straps 16.

The invention provides for the easy and rapid removal of the nether garment merely by a single downward pull thereon, which is sufficient to withdraw the heads 12 from the slots 4. Owing to the shortness of the bodice member and the concave cut 3 therein, this member does not become soiled and need not be changed. Also, the absence of excessive material contributes to the comfort of the infant as well as to the economy of the device. It is obvious that a soiled nether garment is readily replaced by a similar garment. The infant does not soil the bodice, and the diaper alone can easily be washed and ironed in a few minutes. The flat lining is preferably separated and rinsed, while the cloth portion is laundered. The bib is washed in like manner.

The diaper herein shown can be applied to any shirt or blouse having the concave cut 3, the ties 5, and slits 4. Even an inferior material may be used for the lining 9. In such case, good results are obtained by merely inserting a paper napkin or the like between the lining and the cloth.

The tabs 12 remain locked even if they fold downward, and do not pull up by the kicking and squirming of the infant. The danger of open safety pins is removed.

The diaper can be fastened in the dark and during black-outs since the slits and tabs can be located by feel. The attaching of the tabs requires less operations than safety pins. Hence, the baby is not handled so much and is less likely to become irritable. The rapid removal of the diaper by pulling exposes the infant less to catching cold.

Owing to the compactness and good fit of the diaper, only the diaper and the corresponding part of the infant's body become soiled. Consequently, the changing of the diaper is a cleaner operation than heretofore, the bodice is not as likely to become soiled, and the infant does not require such frequent bathing.

The water-proof lining of the diaper, not coming into contact with the infant's body, does not slip and slide as do rubber panties. Also, it cannot become too tight, as it is held by the cloth portion which in turn affords ample leg room at the open edges.

The same construction, in larger sizes, can be satisfactorily worn by bed-ridden adults who are helpless. It is more comfortable and sanitary and less annoying than methods now employed. Grown children and even adults afflicted with certain ailments will also benefit greatly by using the diaper combination.

Another feature of the invention is that there is considerable saving of material in the nether garment which obviously requires less material than a conventional diaper.

Although a specific embodiment of the invention has been illustrated and described, it will be understood that various alterations in the details of construction may be made without departing from the scope of the invention as indicated by the appended claims.

What I claim is:

1. A diaper combination comprising a bodice member having a series of horizontal slots near its lower edge, a nether sheet adapted to be doubled over, and tabs at the ends of said sheet, said tabs having heads wider than said slots and adapted for insertion therein.

2. A diaper combination comprising a bodice member having a series of horizontal slots near its lower edge, a nether sheet adapted to be doubled over, and tabs at the ends of said sheet, each tab consisting of a neck substantially as wide as one of said slots and a head wider than a slot.

3. A diaper combination comprising a bodice member having a series of horizontal slots near its lower edge, a nether sheet adapted to be doubled over, and tabs at the ends of said sheet, each tab consisting of a neck substantially as wide as one of said slots and a head wider than a slot, with lateral edges forming acute angles with the longitudinal edges of the corresponding neck.

4. A diaper combination comprising a bodice member having a series of horizontal slots near its lower edge, a two-ply nether sheet closed at two opposite edges, said edges having slots therethrough corresponding to the first named slots, a lining sheet within said two-ply sheet, and tabs on the ends of said lining sheet and extending through the last named slots and adapted for insertion in the first named slots.

5. A diaper combination comprising a bodice member having a series of horizontal slots near its lower edge, a two-ply nether sheet closed at two opposite edges, said edges having slots therethrough corresponding to the first named slots, a lining sheet within said two-ply sheet, and tabs on the ends of said lining sheet and extending through the last named slots and adapted for insertion in the first named slots, said tabs having heads wider than said slots.

WILMA GESUND.
